UNITED STATES PATENT OFFICE.

GRANT C. McCUNE, OF CHICAGO, ILLINOIS.

AUTOMATIC FORCE SIGHT-FEED PUMP FOR LUBRICATORS.

SPECIFICATION forming part of Letters Patent No. 758,460, dated April 26, 1904.

Application filed April 27, 1903. Serial No. 154,500. (No model.)

To all whom it may concern:

Be it known that I, GRANT C. McCUNE, a citizen of the United States, residing at Chicago, in the county of Cook and State of Illinois, have invented certain new and useful Improvements in Automatic Force Sight-Feed Pumps for Lubricators; and I do declare the following to be a full, clear, and exact description of the invention, such as will enable others skilled in the art to which it appertains to make and use the same.

This invention relates to improvements in automatic force sight-feed pumps for lubrication.

15 The object of the invention is to provide a pump for this purpose which may be adjusted to give any desired feed and to provide means whereby such adjustment may be made without stopping the pumps.

20 A further object is to do away with the customary throttling of the feed by needle-point valves and also to provide a pump which will feed the same number of drops per stroke irrespective of any change whatever in the temperature of the oil.

25 A further object is to provide such a pump which will be simple in construction, positive in action, and particularly adapted for forcing oil into cavities or chambers which are under pressure.

30 With these and other objects in view the invention consists of certain novel features of construction, combination, and arrangement of parts, as will be more fully described, and particularly pointed out in the appended claims.

35 Figure 1 is a vertical sectional view of a lubricating-oil cup embodying the invention and showing one side of the pump adjusted 40 to full working position and the opposite side adjusted to a non-working position, the plungers of both sides being shown at the end of a downstroke. Fig. 2 is a similar view showing the plungers at the end of an upstroke.

45 In the drawings, 1 denotes the oil-cup, consisting, preferably, of the usual glass cylinder closed at its upper end by a metal cap 2 and having its lower end seated in a base-plate 3.

4 denotes a centrally-disposed guide-tube

50 having a screw-threaded engagement with the cap 2 and the base-plate 3.

5 denotes a vertically-reciprocating connecting-rod slidably mounted in the tube 4 and connected at its lower end with a yoke 6, which is engaged by a crank 7 on the end of 55 a crank-shaft 8, journaled in a laterally-projecting tubular arm 9, formed integral with a vertically-disposed tubular standard 10, which has a screw-threaded engagement at its upper end with the base-plate 3 of the cup, the said 60 tubular standard being adapted to inclose the lower end of the rod 5, the yoke 6, and crank 7. On the opposite end of the shaft 8 is mounted a ratchet-wheel 12, the teeth of which are adapted to be engaged by a pawl or dog 65 13, carried by a depending swinging arm 14, provided at its upper end with a laterally-projecting tubular arm or sleeve 15, which is adapted to be inserted in the tubular arm 9 and through which the crank-shaft 8 is adapt- 70 ed to pass.

The lower end of the depending swinging arm 14 is connected to one end of a rod 16, the opposite end of which is connected to a movable part of the engine or machine to 75 which the device is attached.

18 denotes an upwardly-projecting arm rigidly mounted on the tubular arm 9 and carrying at its upper end a pivoted pawl 19, which engages the teeth of the ratchet-wheel 12 at 80 the upper side thereof.

The object of the pawl 19 is to prevent retrograde movement of the ratchet-wheel 12. A handle or knob 20 is fixed to the ratchet-wheel, whereby the same may be operated by 85 hand, if desired.

The lower end of the tubular supporting-standard 10 is suitably connected to a stationary part of the engine and supports the cup and the mechanism attached thereto.

To the upper end of the connecting-rod 5 is attached a cross-head 21, to the ends of which are connected vertically-disposed operating-rods 22, the lower ends of which extend down through openings in the cap 2 and into the oil-cup 1 and are connected to a cross-head 23, on which is formed a vertically-disposed guide-sleeve 24, which is adapted to engage

and slide upon the tube 4. The lower ends of the operating-rods 22 extend below the cross-head 23 and are screw-threaded for a purpose hereinafter to appear. Milled heads 22^a are provided for the rods 22 to enable them to be readily turned. The upper one of each pair of said milled heads is a jam-nut to retain the adjustment.

In the base-plate 3 are formed one or more cylindrical cavities 25, two of which are shown in the drawings; but any number may be employed. In the base of each of the cylindrical cavities is mounted a vertically-disposed tubular standard or guide-rod 26, on the upper ends of which are arranged conical valves 27, preferably in the form of screws, the lower ends of which have a threaded engagement with the upper ends of the tubular standards 26, and the conical heads of the screws being adapted to form the valves. The stems of said valves have oil-passage channels 27^a. Channels are also in the ends of the guide-rods 26 opposite the channels 27^a. Below the lower threaded ends of the screws the standards 26 are provided with an annular series of ports or passages 28.

29 denotes vertically-reciprocating sleeves, which are adapted to have a sliding engagement with the standards 26 and to be connected to and operated by the cross-head 23. On the upper ends of the sleeves 29 are formed pump-cylinders 30, which reciprocate with said sleeves.

31 denotes cup-shaped pistons open at their upper ends and provided in their lower ends with valve-seats 32. The pistons 31 are adapted to be mounted in the pump-cylinders 30, and upon these pistons the said cylinders are adapted to reciprocate. The valve-seats 32 in the lower ends of the pistons are adapted to have a sliding engagement with the screw-head valves 27, and when said valves are open the pistons are adapted to be supported upon the upper ends of the tubular standards 26, and when the valves are closed the pistons are raised until the valve-seats therein are brought into engagement with the valves, thereby closing the valve-opening.

Near the upper end of the pistons is formed an exterior annular groove in which is seated an expansive ring 33, which is adapted to engage an interior shallow annular groove 34, formed in the upper portion of the pump-cylinders. The upper and lower walls of the groove 34 are slightly beveled.

The engagement of the ring 33 on the pistons with the groove 34 in the cylinders causes the pistons to be moved up or down by the cylinders between the screw-head valves and the tops of the standards 26, and when either of the stops are reached the piston will be held, but the cylinder moves on, the beveled walls of the grooves 34 permitting the cylinders to disengage themselves from the ring 33, as will be understood.

At points above the pump-cylinders the cap 2 of the cup 1 is provided with openings 35, above which are arranged cylindrical glass domes 36, closed at their upper ends by caps 37 and suitably fixed at their lower ends to the cap 2.

38 denotes tubular plungers adjustably mounted upon the sleeves 29. The upper ends of the plunger 38 are provided with laterally-projecting arms 39, which are adapted to have a screw-threaded engagement at their outer ends with the lower threaded ends of the operating-rods 22. This connection of the tubular plungers with the operating-rods and sleeves 29 causes the parts to move simultaneously and as one piece.

As the sleeves 29 and pump-cylinders are reciprocated by the rods 22 the lower ends of the sleeves are adapted to enter the cylindrical cavities 25 in the base-plate, and when the tubular plungers are screwed down upon the ends of the rods 22 to a working position, as shown at A in the figures of the drawings, the ends of the said plungers will on the down-strokes thereof enter the cylindrical cavities 25, forcing the oil contained therein out through valved discharge-ports 40, arranged in the base of said cylindrical cavities, and into the feed-tubes 41, which are connected at their lower ends to the discharge-ports 40.

The tubes 41 project upwardly and are formed at the top with an arched or curved delivery end, which passes through the caps 37 and opens into the domes 36 above and in line with the open ends of the pump-pistons 31. The oil from the cylindrical cavities 25 which has been forced out through the valved ports 40 is forced upwardly through the tubes 41 and drops into the open pistons 31 at each down-stroke of the plungers 38. The number of drops forced out of the end of the tubes 41 is determined by the position of the plungers 38 upon the sleeves 29, which position is regulated by means of the screw-threaded engagement of the plunger-arms with the lower ends of the operating-rods 22, as hereinbefore described. The lower the plungers are adjusted the more oil will be displaced and forced out of the cylindrical cavities 25 into the lower ends of the tubes 41 and a correspondingly larger discharge will occur from the upper ends of the tubes, and vice versa.

The downstroke of the sleeves and plungers which forces the oil from the cylindrical cavities 25, as just described, also causes a down-stroke and suction of the pump-cylinders, simultaneously lowering the pistons by means of the expansive ring and groove connection therewith and opens the valves in the lower ends of the same, allowing the oil which has been dropped into the piston to be sucked out of the same and into the pump-cylinder, whereupon on the upstroke of the pump-cylinders this oil is forced through the annular series of ports or passages 28 and into the

tubular standard 26 through the same and past the check-valves 42 and 43, arranged in the lower end of tubular standard and in the discharge-passage from the same, and from 5 thence the oil is delivered to the place of use.

In the side of the cup 1, as indicated at B, the tubular plunger is shown as adjusted to its extreme height, and in this position, as will be seen, it does not enter the cylindrical cavity at all. Consequently no oil is being forced from this side of the cup. It will also be understood that by adjusting these plungers any one or all of the feeds may be cut off or operated at will and also that any degree of feed may be had, this adjustment being accomplished by rotating the operating-rod 22 and screwing the plungers up or down upon the lower threaded ends of the rods without stopping the working of the pump.

20 In the arrangement of the parts it will be seen that there are no joints to be packed, except where the cap and base-plate are fitted to the glass cylinder of the cup, and that the working parts being all inside of the cup and 25 in the oil are self-lubricating. Furthermore, said parts, as well as the feed, are in plain sight and the working of same may be observed at all times.

While a pawl-and-ratchet mechanism is 30 herein shown and described as the means for actuating the parts, it is obvious that other means may be employed to accomplish the same purpose.

From the foregoing description, taken in 35 connection with the accompanying drawings, the construction and operation of the invention will be readily understood without requiring a more extended explanation.

Various changes in the form, proportion, 40 and the minor details of construction may be resorted to without departing from the principle or sacrificing any of the advantages of this invention.

Having thus fully described my invention, 45 what I claim, and desire to secure by Letters Patent, is—

1. An oil-chamber having an oil-receiving cavity, a plunger to operate in said cavity to force oil therefrom, means to operate the 50 plunger, and an element, carried by and adjustable on the plunger and coacting therewith and with the cavity to vary and predetermine the quantity of oil forced from the cavity by the effective portion of the stroke of 55 the plunger, substantially as described.

2. An oil-chamber having an oil-receiving cavity forming a cylinder, a passage leading from said cavity, a tubular guide extending through said cavity and having a closed end 60 and an intersecting passage 28, a tubular plunger operating on said tubular guide and in said cavity to force oil from the cavity through said first-mentioned passage, a hollow piston in the enlarged upper portion of said tubular 65 plunger carried by said tubular guide and

adapted to receive oil from said first-mentioned passage, and having a valved passage communicating with the interior of said enlarged portion, whereby the oil forced by the plunger from the receiving-cavity is also 70 forced by said hollow piston through the tubular guide, substantially as described.

3. In a device of the character described, the combination with an oil-chamber, having one or more cavities or openings formed in the 75 bottom of the same, and adapted to contain oil, one or more reciprocating plungers adapted to work in said cavities to force the oil from the same, pumping mechanism arranged on the upper ends of said plungers and adapted to be operated thereby, means for conducting the oil forced from said cavities to said pumping mechanism, and means for conducting the oil from said pumping mechanism to the place of use, substantially as described. 80

4. In a device of the character described, the combination with an oil-chamber having one or more cavities formed in the bottom of the same and adapted to contain oil, of tubular guide-standards projecting upwardly from 90 said cavities, plungers adapted to reciprocate upon said standards to force the oil from said cavities, pump-cylinders carried by the upper ends of said plungers and adapted to reciprocate therewith, hollow pistons arranged 95 upon the upper ends of said tubular standards and adapted to operate in conjunction with said cylinders, valved passages through said pistons, valved passages adapted to conduct the oil forced out of said cavities to said hollow pump-pistons, ports formed in the upper ends of said tubular standards, through which said oil is forced by said pistons into 100 said standards, and valved passages formed at the lower ends of and communicating with 105 said tubular standards, whereby the oil is conducted to place of use, substantially as described.

5. In a device of the character described, the combination with an oil-chamber having one 110 or more cavities formed in the bottom of the same, one or more reciprocating plungers adapted to work in said cavities to force the oil from the same, means for independently moving any one of said plungers out of working position, pumping mechanism carried and operated by said plungers, valved passages adapted to conduct the oil forced from said cavities to said pump mechanism, and means for reciprocating said plungers. 115

6. In a device of the character described, the combination with an oil-chamber having one or more cavities formed in the bottom of the same, one or more reciprocating plungers adapted to work in said cavities to force 125 the oil from the same, means for adjusting said plungers to force more or less oil out of said cavities, pumping mechanism carried and operated by said plungers, valved passages adapted to conduct the oil forced 130

from said cavities to said pumping mechanism, valved passages for conducting the oil from said pumping mechanism to service-pipes, and means for reciprocating said plungers, substantially as described.

7. In a device of the character described, the combination of an oil-chamber having one or more cavities formed in the bottom of the same, one or more reciprocating two-part plungers, adapted to work in said cavities to force the oil from the same, pumping mechanisms carried and operated by said plungers, valved passages adapted to conduct the oil forced from said cavities to said pumping mechanisms, valved passages for conducting the oil from said pumping mechanisms to service-pipes, vertically-reciprocating cross-heads adapted to carry the respective parts of said plungers, a vertically-reciprocating connecting-rod carrying at its upper end a cross-head, and operating-rods connected to and carried by said cross-heads and connected to the plungers and arranged to adjust the parts of the latter to force more or less oil from said cavities or to move said plungers entirely out of operation, and means for actuating said connecting-rod, substantially as described.
8. In a device of the character described, the

combination with an oil-chamber having one or more cavities formed in the bottom of the same and adapted to contain oil, of one or more reciprocating plungers adapted to work in said cavities to force oil from the same, pumping mechanisms carried and operated by said plungers for forcing the oil delivered from said cavities to service-pipes, a vertically-reciprocating cross-head adapted to carry said plungers, a vertically-reciprocating connecting-rod carrying at its upper end a cross-head, operating-rods adapted to connect said cross-heads, a suitably-mounted crank-shaft connected to and adapted to operate said rod, a ratchet-wheel carried by the opposite end of said crank-shaft, a suitably-mounted swinging arm carrying a pawl which is adapted to engage and turn said ratchet-wheel and crank-shaft, means for oscillating said arm, and means for preventing a retrograde movement of said ratchet-wheel, substantially as described.

In testimony whereof I have hereunto set my hand in presence of two subscribing witnesses.

GRANT C. McCUNE.
